United States Patent Office

Des. 208,654

Patented Sept. 19, 1967

208,654

PLATE OR SIMILAR ARTICLE

Ryotaro Takeoka, 221 Kitayamoto-cho,
Nishikasugai-gum, Aichi-ken, Japan

Filed Mar. 6, 1967, Ser. No. 6,081

Term of patent 7 years

(Cl. D44—15)

The figure is a plan view of a plate or similar article showing my new design, a portion of the design being shown between dot and dash lines and a repeat portion being shown between dotted lines.

The plate is of a conventional configuration when viewed from the side and bottom thereof.

I claim:

The ornamental design for a plate or similar article, substantially as shown and described.
